VALVE CONTROL PANEL FOR BEVERAGE DISPENSING NOZZLE

Wayne Easley, Moraga, Calif., assignor to Seven-Up
Bottling Company of Oakland, Oakland, Calif., a cor-
poration of California

Filed Nov. 18, 1964, Ser. No. 82,680

Term of patent 14 years

(Cl. D2—3)

FIGURE 1 is a perspective view of a valve control panel for beverage dispensing nozzle showing my new design;

FIGURE 2 is a top elevational view thereof; and
FIGURE 3 is a side elevational view thereof.

The broken line representations of a dispensing nozzle in FIGURE 1 and of a portion of a nozzle in FIGURE 3 and letters and numerals in FIGURES 1 and 2 are for purposes of illustration only.

I claim:

The ornamental design for a valve control panel for beverage dispensing nozzle, substantially as shown and described.
